the said door or the like, and to provide a door knocker which is particularly simple and economical in construction, and highly efficient and durable in use; and to this end, it consists in the novel combinations and means hereinafter set forth and claimed.

UNITED STATES PATENT OFFICE

2,523,158

DOOR KNOCKER

John Starp, Cleveland Heights, Ohio

Application April 7, 1949, Serial No. 85,978

1 Claim. (Cl. 116—172)

1

The invention constituting the subject matter of this application is a door knocker mounted on a unique base plate forming a part thereof.

My invention has for its object to provide an improved door knocker which is particularly simple and economical in construction, and highly efficient and durable in use; and to this end, it consists in the novel combinations and means hereinafter set forth and claimed.

In describing this invention, reference is had to the accompanying drawing in which like characters designate corresponding parts in all the views.

Figure 1 is a view in elevation of the base plate with the door knocker mounted therein.

Figure 2 is a sectional view on line 2—2 in Fig. 1.

According to my invention I employ a base plate or support 1 made of cast metal, plastic or other suitable material. In the base plate there may be provided three recesses as at 2, 3 and 4. The recess 4 is provided to accommodate a scratch pad, while the recesses 2 and 3 are provided to receive and hold the number of a house or a suite and the name of the occupant thereof. The scratch pad may be held in place by means of the bolts and nuts 5 and 6, however, any other suitable practical means may be used.

In the base plate there is removably mounted a hollow block 7 having a smooth blind bore 8 therein, in the bottom of which there is provided a raised portion 9 against which the enlarged head of the plunger strikes. The block is provided with an annular flange 10, an upper threaded portion 11, and a lower threaded portion 12, that extends through the base plate and slightly below the lower surface 13 of the base plate. The hollow block is held in assembled relationship in the base plate by means of a speed nut 14 or the like that clamps the plate between the underside of the flange and the upper surface of the speed nut.

In the hollow block there is provided a plunger 15 with a stem 16 and an enlarged head 17 adapted to engage the raised portion 9 in the hollow block when manually knocked down thereagainst. On the stem of the plunger there is mounted a washer 18 and a helical spring 19. In the stem there is provided a transverse removably mounted pin 20. The helical spring is disposed between the pin and the washer. The helical spring is of the expandable type and normally holds the plunger in the position shown in the sectional view in Figure 2.

A detachably mounted cap 21 is threaded on

the upper threaded portion of the hollow block, and is provided with a seat 22 against which the transverse pin engages and which limits the upward movement of the plunger in the cap and also in the hollow block.

The plunger is provided with a knob 23, which is detachably threaded on the upper end of the stem of the plunger.

It has been previously noted that the hollow block projects slightly below the bottom surface of the base plate, so that when it is mounted on the door or the like, the two lower screws used to assist in holding it in place, and for which the two through holes 24 and 25 are provided therein causes the hollow block to be firmly held against the surface of the door. When the plunger is given a quick stroke with the hand, the end of the plunger contacting the upper surface of the upstanding portion in the hollow block 20 imparts a knock that is very intense and free from rattle.

The operation of the device is as follows:

The base plate with its assembled knocker therein is screwed in place on a door or the like. 25 When it is necessary to use the knocker, the knob thereof is given a sharp stroke with the hand which drives the plunger down in the hollow block against the upstanding portion in the bottom thereof which imparts an intense sound. 30 When the hand is removed the coil spring being of the expandable type causes the plunger to return to its initial position. Its upward movement is limited by the seat in the cap. If the spring becomes exhausted, a new spring may be easily installed by removing the knob from the plunger and the cap from the hollow block and the transverse pin in the stem of the plunger. A new spring may then be installed and the parts assembled.

While I have shown and described a preferred arrangement, it will be readily understood that changes and modifications therein may be found desirable or essential in meeting the various exigencies of use, and I desire to be understood as reserving the right to make any and all such changes or modifications as may be found desirable or essential, in so far as the same may fall within the spirit and scope of the invention as expressed in the accompanying claim when broadly construed.

Having thus described my invention, what I claim is:

A door knocker, comprising, in combination, a hollow base member having a through opening therein intermediate its width and adjacent

one end thereof, a hollow cylindrical knocker member having a smooth internal bore therein, and an upstanding plunger engaging portion in the bottom thereof, and also having an upper externally threaded portion and a lower externally threaded portion, a flange between the aforesaid threaded portions, the lower portion mounted in the through opening in the base and positioned by the flange engaging the upper surface of the hollow base member so that the end of the lower threaded portion extends slightly below the bottom surface of the base member, a nut threaded onto the lower threaded portion and adapted to secure the knocker member in the base member, a plunger having a stem portion slidably mounted in the knocker member, a washer slidably mounted on the plunger stem and seated on the upper end of the knocker member, a helical spring mounted on the plunger stem, its lower end seated on the upper surface of the washer, a transverse pin in the plunger stem, the upper end of the helical spring engaging the transverse pin, a cap having a through opening in the top thereof threadedly engaging the threaded knocker member, the transverse pin

engaging the under surface of the cap, the pin adapted to limit the upward movement of the plunger when returned to initial position after being struck to produce a knock by the plunger engaging the upstanding portion in the bottom of the hollow cylindrical knocker member, and a knob on the upper end of the plunger stem adapted to receive a blow in producing a knock.
